RUDOLPH W. MILLER, OF BROOKLYN, NEW YORK

CRIBBING

Application filed July 26, 1929. Serial No. 381,127.

This invention relates to cribbing adapted to be used to brace the sidewalls of excavations and has for an object the provision of cribbing or framework of this character which can be readily placed and removed, which is composed of sectional members of convenient design for employment in excavations of various areas and depths, and which is inexpensive, durable and rigid.

10 The present common method of bracing the sidewalls of earthen excavations is to drive flat timber piling down the side walls behind longitudinal beams or timbers braced against the opposite sidewall of the excavation. The nature of the interior bracing for this framework is such that the working space within the excavation is unduly limited. The placing of the framework is a laborious task. The timber piling framework is not well suited for deep excavations with relatively 15 weak sidewalls where the framework must follow the excavation downward, this necessitating long piling with high platforms for the workmen to stand on in starting and not readily permitting bracing of an excavation 20 deeper than a single length of piling.

Various fabricated cribbings have been proposed for this purpose but so far as known they have not proven entirely satisfactory. At all events they have not attained wide use and wooden cribbing continues to be used almost exclusively.

The present invention aims to avoid all of these difficulties and objectionable features 35 and the manner of accomplishing these desirable results will be obvious to those skilled in the art from a consideration of the following description and illustration of an exemplary embodiment of the invention, the embodiment shown being particularly adapted for long narrow excavations such as 40 trenches or ditches, this being the type of excavation most frequently requiring cribbing.

45 In the accompanying drawings forming a part of this specification,

Figure 1 is a perspective view of the apparatus applied to two sides of an excavation, the other two sides being omitted since 50 they are identical;

Figure 2 is a side elevation of the sectional members laterally separated from each other;

Figure 3 is an elevational view showing an assembly of five side members instead of 55 three as in Figures 1 and 2;

Figure 4 is a vertical section of a corner member, the section being taken on the line 4—4 of Figure 3;

Figure 5 is a vertical section taken on the line 5—5 of Figure 3;

Figure 6 is a vertical section taken on the line 6—6 of Figure 3; and

Figure 7 is a vertical section taken on the line 7—7 of Figure 2.

Referring to the drawings and particularly to Figure 1 which shows an assembly of the apparatus as used in a long trench, there is a plurality of plates 10 all secured together into a rigid box-like structure by latches 12 and keepers 14. The latch and keeper construction in this particular embodiment varies somewhat among the several plates but its essential function—that of providing quick assembly and dismantling and rigidity 75 of the assembly—remains the same, whatever the embodiment may be. Further, in this particular embodiment, the latch members are shown to be permanently attached to the plates but this is not indispensable. The latches may be separate units cooperating with the keepers to connect all of the plates together.

To proceed with the description of the particular embodiment selected, and still referring to Figure 1, the assembly, besides being made up of sectional pieces or plates forming a single length or tier of framing or unit of casing length, also may comprise a plurality of tiers or units of casing length. These tiers 80 in turn are connected together in such a manner as to be quickly assembled and dismantled. Bottom hook flanges 16 on upper tier plates and top hook flanges 18 on lower tier plates have been found convenient and adequate. If the outside size of the excavation is to be preserved one of the mating plates may be provided with an off-set 18a to keep the plates in alignment.

If the nature of the material composing the 100

side walls of the excavation makes it desirable, the top tier of plates—and thus the whole assembly—may be supported on sills or beams 20, the plates being provided with lateral flanges 22 adapted to rest upon and if necessary to be secured to the beams. Holes 24 are provided in the flanges 22 for taking nails, screws or bolts entering the beams for this purpose.

10 For convenience of handling when the plates are large and heavy, they may be provided with holes 26 to receive lifting hooks.

15 To brace the structure across its width the plates may at intervals along the side be provided with keepers or straps 28 to receive the bent ends 30 of U-shaped struts 32. In Figure 1 only one end of the strut is shown so engaged, the near side wall having been omitted for illustrative convenience.

20 Often a platform or landing is desirable, either for workmen to stand on or for supporting excavated material, tools, structural parts and the like. A simple and easily installed platform element is indicated at 34.

25 It is U-shaped and the bent ends 36 are adapted either to fit within the bottom hooks 16 of the plates where these hooks are not occupied by a lower plate, or to rest upon the shoulder formed by the inverted hooks 18, in the latter case the cross bracing preventing slippage. Only one platform element 34 is shown but obviously any number may be employed.

30 Referring to Figures 2 to 7, certain specialized shapes are illustrated. In Figure 2 the end plates 10a are shown to be provided with slots 14a serving as keepers for latches or hooks 12a formed on the corner plates 10b, which in this case are reverse hand duplicates. The end plates are made just of a width to fit 35 the width of the particular excavation but in view of the structural showing of latches and hooks for the side plates given herein, one skilled in the art could readily adapt the end plates to sectional construction for wider excavations.

40 The corner plates have keepers 14b adapted to receive the protruding latch ends 12b of bars 28a riveted to a center side wall plate 10c. The central part of the bar 28a is bent out to form the loop 28 for the end of the cross strut 32. If desired, the latches 12b may be provided with hooks 18 to prevent the casing unit spreading outward after assembly.

45 The plates of the lower tier shown in Figure 2 are in all respects like those of the upper tier except that they have hooks at both ends instead of a lateral flange and hook and that they are provided below the top hook 18 with the offset 18a.

50 The construction shown in Figure 3 is the same as that in Figure 2 except that five side plates instead of three are employed, the structural variations in hooks and keepers being obvious. Only one plate of different construction is required—the center one, 10d—

55 and this has keepers 14b on both vertical edges. If more plates are required the use of appropriate ones of those already described will take care of any length of excavation.

60 Figures 4 to 7 show sections which assist in an understanding of the construction here-
tofore described. It is believed that no de-
scription either of these figures or of the pro-
cedure of assembling and dismantling the
apparatus is required in view of what has
75 already been said.

70 It is to be understood that various changes
and modifications may be made without de-
parting from the spirit of the invention as
set forth in the subjoined claims.

80 What I claim is:

1. Cribbing for excavations, comprising
sectional mating members including an end
member having slots therein, a side member
mating therewith having hooks insertable
through said slots, said side member having
keeper brackets thereon, and a second side
member mating with the first side member
provided with latches engaging said keepers.

2. Apparatus as set forth in claim 1 which
further includes a third side plate provided
with keepers on both edges cooperating with
the latches of adjacent plates.

3. Cribbing for excavations, comprising in
combination, spaced retaining plates provided
with upturned hooks thereon and a shelf of
U-shape insertable in the hooks of said plates.

35 In testimony whereof, I have signed my
name to this specification this 19th day of
July, 1929.

100 RUDOLPH W. MILLER.
